PARLOR STOVE.

No. 15,648.

Patented Dec. 30, 1884.

N. S. VEDDER PATTERN WORKS
TROY, N.Y.

UNITED STATES PATENT OFFICE.

H. CLAY BASCOM, OF TROY, NEW YORK.

DESIGN FOR A PARLOR-STOVE.

SPECIFICATION forming part of Design No. 15,648, dated December 30, 1884.

Application filed October 20, 1884. Term of patent 7 years.

To all whom it may concern:

Be it known that J. H. CLAY BASCOM, a citizen of the United States, residing in the city of Troy, in the county of Rensselaer and State of New York, have invented and produced a new and original Design for Parlor-Stoves, of which the following is a specification, reference being had to the accompanying engraving of a stove illustrating said design.

This design embraces several new and distinct parts and combinations of parts, which go to make up the whole design, as hereinafter specified.

15 The vase on the cover of the stove is not a part of this design. One distinctive part is the shape and ornamentation of the raised oval cover A, consisting of the flat top *a*, the concave-curved part *b*, having the series of ornaments *b'*, and the convexly-curved part *c*, having the series of semi-rosettes *c'* along its lower border. Another part relates to the shape and ornamentation of the raised panel B of rectangular form, and consisting of the 20 outer interrupted border-headings *d* and rectangle corner ornaments, *d'*, the plane panel-surface *e*, and the round-cornered compound ornamental molding inclosing the said surface *e*, and consisting of the top, bottom, and 25 end bands, *f*, having serrate ornamentations, and the inwardly-projecting corner ornaments *g*, backed by the sub-rosettes *g'*. Another part is the shape and ornamentation of the raised panel-plate C, the same being of 30 general quadrilateral form, and having the truncate or acute angled corner projections *h*, the angular projections *i* at the middle parts of the straight top, bottom, and end edges, the oblong middle name-space, *j*, and the intermediate incut ornamentations, *j'*, in combination with the raised panel B, shaped and ornamented as above specified. Another part is the shape and ornamentation of the upper and 35 lower corner pilasters, D, consisting of the flat surface *k* between the parallel border-headings *k'*, and having the repetitions of the connected ornamented rectangular figure *l*, heart-shape ornamentation *m*, and the fan-form ornaments *n*. Another part relates to the shape and ornamentation of the front door, E, consisting of the upper portion, *o*, curved

convexly, both horizontally and vertically, and having the round-top openings *p*, intermediate ornaments, *q*, and ornamental border *r*, and the lower vertical portion *s*, curved convexly in the horizontal direction, and having the round-top apertures *t* and the ornaments *t'*. Another part is the shape and ornamentation of the end door, F, of a general rectangular form, curved convexly in the horizontal direction, and consisting of the larger upper panel, *u*, having the central compound ornament, *v*, and compound ornamented border-moldings *v'*, the lower panel, *w*, and the intermediate molded surface, *w'*. Another 55 part is the shape and ornamentation of the legs G, consisting of the convexly-curved shield form portion *x*, having the ornamental top band, *y*, and compound pendent ornament *y'*, the contracted part *z*, and the foot *z'*. 60

The whole design embraces the shape and ornamentation of the cover A, top plate, H, the stove-front including the panel B, panel-plate C, pilasters D, and door E, the end including the door F, the hearth-plate I, and the 75 legs.

I claim as new--

1. In a design for a stove, the shape and ornamentation of the cover A, consisting of the parts *a b b' e c'*, as shown and described. 80

2. In a design for a stove, the shape and ornamentation of the raised rectangular panel B, consisting of the parts *d d' e f g g'*, as shown and described.

3. In a design for a stove, the shape and 85 ornamentation of the panel-plate C, consisting of the parts *h i j j'*, in combination with the raised rectangular panel B, having the parts *d d' e f g g'*, as shown and described.

4. In a design for a stove, the shape and 90 ornamentation of the pilasters D, consisting of the parts *k k' l m n*, as shown and described.

5. In a design for a stove, the shape and ornamentation of the front door, E, consisting of the parts *o p q r*, and *s t' t*, as shown 95 and described.

6. In a design for a stove, the shape and ornamentation of the end door, F, consisting of the parts *u v v'*, and *w w'*, as set forth.

7. In a design for a stove, the shape and 100 ornamentation of the legs, embracing the parts *x y y' z z'*, as shown and described.

8. The design for a stove, embracing the cover A, top plate, H, the front including the panel B, panel-plate C, pilasters D, and door E, the end including the door F, the 5 hearth-plate I, and the legs, shaped and ornamented substantially as shown and described.

In testimony whereof I hereunto set my hand, in the presence of two subscribing witnesses, this 17th day of October, 1881.

H. CLAY BASCOM.

Witnesses:

CHARLES H. BENEDICT,

JAMES A. GILMAN.
